UNITED STATES PATENT OFFICE.

ISAIAH H. FARNHAM, OF WELLESLEY, ASSIGNOR TO THE NEW ENGLAND TELEPHONE AND TELEGRAPH COMPANY, OF BOSTON, MASSACHUSETTS.

AUTOMATIC TOLL-BOX.

SPECIFICATION forming part of Letters Patent No. 451,922, dated May 12, 1891.

Application filed February 13, 1891. Serial No. 381,366. (No model.)

To all whom it may concern:

Be it known that I, ISAIAH H. FARNHAM, residing at Wellesley, in the county of Norfolk and State of Massachusetts, have invented 5 certain Improvements in Automatic Toll-Boxes, of which the following is a specification.

This invention relates to coin-controlled toll-boxes for telephone pay-stations of that 10 class in which the call apparatus is freely accessible to the customer, who after making the call and being answered by the operator states the place with which communication is desired, and is then informed of the proper 15 amount of toll and instructed to place the same in a slot or slots designated for the purpose, and wherein the tolls being so deposited are caused to transmit certain distinctive signals to the central or other receiving station, 20 whereby the operator is enabled to ascertain the value of the deposited coin or coins, and as a consequence to check the amounts and to know whether the proper amount has been deposited.

25 Many forms of coin-controlled-telephone apparatus have been devised, but those operating on the above principles seem the most practical. Prior to my invention one way in which the deposition of the coin was enabled 30 to send its distinctive signal whereby any one coin can be distinguished from another has been to include in the battery-circuit of the telephone-transmitter a sufficient number of circuit-breaking contacts, which are 35 normally closed, so that the integrity of the transmitter-circuit may be maintained unimpaired during the operation of said transmitter. The coin in its passage from the slot to the deposit-box, according to its size, acts upon 40 one or more of such contacts, and thereby breaks the circuit of the battery as often as it operates a contact, causing one, two, or more clicks in the receiving-telephone of the distant operator, who, by the number of clicks heard, is 45 apprised of the value of the money deposited. It is necessary to the operation of this coin device that the toll-station receiver be first removed from its switch-hook, so that the telephone branch at such station may be connected with the line, and as the customer 50 has already had to remove the said receiver

to give his order it is only required that he refrain from replacing it while depositing the money. There is, however, a practical defect in this organization—namely, that the several 55 contacts in the direct transmitter-battery circuit are, in fact, so many points of weakness, all of which are likely after a short period of work to develop high resistance and consequently imperfect transmission. As is well 60 known, the transmitter proper and its battery are included in a short local circuit, which also includes the primary helix of an induction-coil, the receiving-telephone and secondary helix of said induction-coil being in a 65 branch of the main circuit controlled by the automatic telephone-supporting switch.

In the construction of automatic toll-boxes embodying the ideas to which I have referred as many as seven delicate contacts have been 70 contemplated, all included in the transmitter local circuit. A very little resistance in the local circuit of a transmitter is fatal to its good work, and each of these contacts is a germ of great resistance.

The object of my invention is to avoid this practical defect, and without interference with the simplicity of the device to provide an apparatus which will be equally effective in determining the value of the money deposited 80 and much less liable to get out of order. I do this by withdrawing the several contacts from the direct transmitter-battery circuit; by providing a shunt-circuit for the said battery; by constructing the several contacts in 85 the form of circuit-closers, so that they are normally open instead of normally closed; by including the said contacts in multiple-arc branches of the said shunt-circuit, and by so arranging them that any coin in its transit 90 shall operate and momentarily close the required number of said branches successively to give the distinctive signal, each contact when operated in turn acting to establish a shunt-circuit for the battery, short-circuiting 95 the transmitter and its primary helix. This plan removes all liability of imperfect speech-transmission due to dirty or lightly-made contacts and gives to the operator a good signal. I have found in practice that the signal produced by shunting the battery from the transmitter and coil is even more distinct than is 100

obtained by breaking the circuit. I find it often useful, also, to provide a vibrator or vibratory circuit-breaker, for producing an unmistakable sound or buzz on the telephone-circuit, and one which cannot be imitated.

In the drawings which form a part of this specification, Figure 1 is an elevation, partly in section, of a telephone outfit provided with a toll device constructed in accordance with my invention. Fig. 2 is a view, including a diagram, of the connections and a front sectional elevation of the chute-inclosing box; and Fig. 3 is a diagram indicating a modification.

15 C is the inclosing case of the toll-depositing apparatus, and a the backboard thereof.

B is the call-bell and generator; T the transmitter, and t the receiving-telephone.

The action of the usual automatic switch 20 when the telephone is removed therefrom is to connect the said telephone and the secondary helix 1 of the induction-coil c in the main circuit and at the same time to close the circuit of the battery b through the transmitter T and 25 primary helix 2. At the top of the casing C is a slot s to receive money, and at the bottom thereof is provided a receptacle D, wherein the coins or tokens fall after traversing the chute e. The chute e is preferably made, as 30 shown, of a series of reversed inclines, along which the coins may roll. They are prevented from falling outwardly by the front guard-strip v, (shown in Fig. 1, but omitted for clearness in Fig. 2,) and are kept in line and maintained on edge partly by reason of the incline 35 of the backboard and partly by means of the several guide-strips g h g' g'', &c.

L L' are respectively the conductors of the telephone branch of the main line, and 7 and 40 8 are the conductors of the battery transmitter-circuit. Two other conductors x and z lead from the poles of said battery, respectively, to constitute the mains of the normally-open shunt-circuit. They have no connection 45 with each other at any time, except when united through any one of a series of circuit-closers or circuit-changers F. I have shown seven such circuit-changers, having, respectively, movable contact-pieces F to F', and fixed 50 contact-pieces f to f', each circuit-changer, therefore, comprising a pair of contact-pieces, which close the shunt-circuit when allowed to make contact with each other. It is not desirable that the larger coins shall actuate 55 all of the circuit-changers, and double guide-strips are therefore provided, in a manner well understood, so that, as in the upper incline, for example, a small coin, as a ten-cent piece, may run behind the inner guide g and 60 strike the contact-lever F, while a coin slightly larger, such as a nickel five-cent piece, will run with its edge over the strip g, but behind the guide-strip h, and will therefore refrain from striking F, but will strike and operate F'. Where it is intended that coins of different sizes shall operate the same circuit-changer, the lever thereof is made with a

plurality of ends, each of which may be associated with its own guide-stop. This, however, is no part of my invention, and is referred to here simply in the way of general application. The movable contact-pieces may, as shown, be provided with retracting springs, or, as is obviously equivalent, they may themselves be formed of springs, or may be hung 75 on arbors or pivots depending on the force of gravity alone to hold them normally away from their complementary fixed points. The wire x of the shunt-circuit is branched to all of the said movable contact-pieces F, as indicated by the alternately long and short broken lines; and the wire z, connected with the opposite pole of the battery, is in like manner branched to all of the fixed contact-pieces f. It is clear, therefore, that the several contacts each form discontinuous bridges between the two conductors x and z of the shunt-circuit, and that where any of the said bridges is made continuous the shunt-circuit is closed, and shunts the current of the battery from the primary helix of the induction-coil, thereby developing a transient but strong current in the secondary of said coil and in the main circuit connected therewith, which current in the distant receiver t² is transformed into sound, manifesting itself as a click.

The several bridges are made continuous when a coin of proper size, passing through the chute, strikes their lever ends, bringing any one of the movable pieces F into contact with its corresponding fixed piece f. The circuit-changers are so arranged, as before explained, that coins of differing denominations will actuate a different number of contacts, 105 and thus close the shunt-circuit a different number of times, and the operator readily understands the value of the coin deposited by the number or order of the clicks heard. Each closure of the circuit is of course but 110 momentary, the resiliency or gravity of the movable contact bringing it back to its normal position as the coin passes on.

I may note here that instead of constructing the shunt-circuit round the battery it may 115 with equal efficiency be arranged round the primary helix of the induction-coil. It will be seen that since none of the circuit-changers or contact pairs are in the direct transmitter-circuit the said circuit cannot be affected by 120 the formation of a high resistance or other fault at any of them.

It is sometimes desirable that a more pronounced and unmistakable sound shall be produced by the operation of the contacts 125 than they alone would be able to effect. For this purpose I provide a vibratory circuit-breaker or buzz-producer M. This I include in the shunt-circuit, and it is adapted to be actuated and to rapidly interrupt and complete the said circuit as soon as the said circuit is first completed through any one of the contact-pairs F. It can of course be connected in either of the conductors x or y at any point

nearer to the battery than the first occurring pair. In the drawings I have shown it as being in the circuit of wires z , which connects with one of its terminals, leading the circuit 5 through the electro-magnet of the instrument M , then by wire r to the automatic vibratory contact-points m , and thence by wire y to the fixed point f' of the nearest pair of contacts. The addition of this device to the toll-box 10 produces a click which is also a buzz and which cannot be mistaken for any other sound. It is of course evident that, if desired, the vibratory circuit-breaker could be so located in the shunt-circuit that only coins of given 15 denomination would produce the buzz, all others producing simply the click or a plurality of clicks. If, for example, the vibrator were included in circuit between the fixed contact-pieces f^6 and f^4 , the dollar piece only 20 being capable of acting on the contact pair F^6 it would only be operated by the transit of the dollar, and the buzz would at all times indicate the deposition of that coin.

In Fig. 3 a modification is shown in which 25 the induction-coil is dispensed with, the transmitter T and battery b being in the main-line circuit $L L'$. The normally-open shunt-circuit is composed of the wires x and y , and can be closed by any of the circuit-closers F , 30 when the battery-current will be diverted from the main circuit.

I claim—

1. The combination, in an automatic toll-box for telephone pay-stations, with the transmitter-battery, the direct circuit thereof, and the induction-coil primary included therein, of a normally-discontinuous shunt-circuit arranged round the said battery or primary helix, and a series of pairs of contacts or circuit-closers adapted, respectively, to close the 35 said shunt-circuit, and thereby to shunt the battery-current from the said primary helix, the several pairs of contacts being arranged in the path of a coin deposited in said box, 40 substantially as described, and for the purposes set forth.

2. The combination, substantially as hereinbefore described, in an automatic toll-box, of a battery, a direct circuit therefor, and a 45 telephone-transmitter included therein with a normally-discontinuous shunt-circuit for the said battery and a series of circuit-closing contacts in multiple-arc branches of said shunt-circuit, each adapted to be actuated by the deposition of a coin and to close the said shunt-circuit, thereby changing the electrical 50 condition of the main circuit and transmitting a signal to a distant receiver included therein.

60 3. In an automatic toll-box for telephone-stations, the combination of a coin-chute with a normally-open shunt-circuit of the transmitter-battery and a series of circuit-

closing contacts therefor arranged successively in the said coin-chute and in multiple 65 arc with each other in said circuit, each one when actuated being adapted to close said circuit, and each provided with an actuating-finger extending to different lengths in the said coin-chute, substantially as described. 70

4. The combination, substantially as hereinbefore described, in an automatic telephone-toll box, of a transmitter-circuit including a transmitter, a battery therefor, and the primary helix of an induction-coil with a normally-open shunt-circuit of said battery, a coin-chute, and circuit-changers located successively therein and adapted to be operated by coins traversing said chute, each circuit-changer being adapted when so operated to 75 close said shunt-circuit, and thereby to send a signal over a circuit connected with the secondary helix of said induction-coil. 80

5. In an automatic toll-box for telephone-stations, a series of circuit-closers located 85 successively in a coin-chute, one or more of which are adapted to be operated by the passage of coins through said chute, according to the size of said coins, a battery, a direct transmitter-circuit for said battery, including 90 a transmitter and the primary helix of an induction-coil, and an independent but normally-open circuit, also connected with said battery, including the said circuit-closers, in parallel with each other and adapted to 95 be closed by the operation of any one of them, and thereupon to divert the current of said battery from said transmitter-circuit for the purpose of sending a signal, substantially as described. 100

6. In an automatic toll apparatus for telephone-stations, the combination of a battery, a transmitter, and one helix of an induction-coil in circuit therewith, an independent signaling-circuit, also connected with said battery and constituting a normally-open shunt-circuit of low resistance therefor, an automatic vibrating circuit-breaker included in said signaling-circuit, and a series of circuit-closers arranged in line in a chute and in 110 parallel in said independent circuit, one or more of said circuit-closers being adapted to be operated by coins traversing said chute, and when operated to close the said independent circuit through the said vibratory 115 circuit-breaker for the purpose of inducing signaling-currents in the secondary circuit of said induction-coil, substantially as described.

In testimony whereof I have signed my name to this specification, in the presence of 120 two subscribing witnesses, this 5th day of February, 1891.

ISAIAH H. FARNHAM.
